Primary Examiner — David Muller*Assistant Examiner* — Nathan Johnston(74) *Attorney, Agent, or Firm* — Baker Botts L.L.P.(57) **CLAIM**

The ornamental design for a vapor compression dehumidifier, as shown and described.

DESCRIPTION

FIG. 1 is a perspective view of the vapor compression dehumidifier;

FIG. 2 is a front elevation view thereof;

FIG. 3 is a left side elevation view thereof;

FIG. 4 is a right side elevation view thereof;

FIG. 5 is a rear elevation view thereof;

FIG. 6 is a top view plan view thereof; and,

FIG. 7 is a bottom view plan view thereof.

The broken line showing a vapor compression dehumidifier is included for the purpose of illustrating portions of the "article" and forms no part of the claimed design.

1 Claim, 6 Drawing Sheets(56)
